UNITED STATES PATENT OFFICE.

JOSEPH C. KANAK, OF CHICAGO, ILLINOIS.

HOT-AIR FURNACE.

Application filed October 18, 1922. Serial No. 594,253.

To all whom it may concern:

Be it known that I, JOSEPH C. KANAK, a citizen of the United States, and a resident of the city of Chicago, county of Cook, and State of Illinois, have invented certain new and useful Improvements in Hot-Air Furnaces, of which the following is a specification.

My invention relates to new and useful improvements in hot air furnaces, and more particularly to a circulation forcing device or apparatus adapted to be installed in any hot air furnace.

The object of the invention is to provide a simple and inexpensive apparatus to be used in connection with a warm air furnace, for the purpose of stimulating the air circulation within the furnace by means of an additional amount of cool air delivered by said apparatus to said furnace at a greater velocity than that at which the air normally circulates in the furnace and system by its own gravity, in order to produce more comfort to the user and a reduction in the amount of fuel used.

Other objects will appear hereinafter.

The invention consists in the combinations and arrangements of parts hereinafter described and claimed.

The invention will be best understood by reference to the accompanying drawings forming a part of this specification, and in which,

Fig. 1, is a plan view of my device mounted in position on the furnace casing, parts being broken away;

Fig. 2, is a vertical cross-section taken on line 2—2 of Fig. 1,

Fig. 3, is a vertical longitudinal section taken on line 3—3 of Fig. 2, and

Fig. 4, is a side elevation of my device.

In the drawings I have shown my device mounted in an opening 6 suitably provided in the outer shell or casing 7, which is spaced a distance outward from the fire pot 8 of the usual hot air furnace.

The device or apparatus comprises an outer housing 10 provided at one end with a curved flange 11, fastened to the furnace casing with bolts or other suitable fastening means, and provided at its lower end with a curved flange 12 bearing against the casing 7 and resting on the usual lower rim 13 of the furnace. The sides of the housing are fastened onto the furnace casing with clamping means in the form of a pair of

metal members 14 having a plurality of folds or overlapping flanges, the two inner folds 15 and 16 of which are placed in the opening 6 and firmly clamped upon the casing 7, as shown in Fig. 1, and the outer, laterally extending folds or flanges 17 of which are then bolted or otherwise suitably fastened onto the sides of said mounting. The extended upper and lower flanges 11 and 12, and especially the folded clamping members 14, provide means for conveniently mounting my device upon the casings of furnaces of various sizes, shapes, and makes, and for properly mounting my device in openings 6 even though such openings are not cut to exact size and shape.

An air directing member 18 is mounted within said housing, preferably by fastening its upper and lower walls to the walls of said housing, and has an upwardly curved inner or front wall 19 provided with an inwardly and downwardly extending lip 20 cut from said wall forming a laterally extending slot 21 beneath said lip, several such lips and slots may be provided if desired, and the upper and inner end of said member 19 is formed into an opening or air outlet. The arrangement of the wall 19 and lip 20, and the slot 21 and upper opening, form effective means for directing the air diagonally upwards against the outer surface of the fire pot, thereby forcing the warmer air, near the fire pot, directly upwards and considerably increasing the speed of circulation of the air. The member 18 is spaced inward from the walls of the housing, thereby forming an air passage 22 on each side of said member, which serves as an intake to permit the passage of warm air from the interior of the furnace casing to mingle with the colder air drawn into the housing from the outside, and thus have the air partly warmed when delivered from the member 18 against the fire pot.

Intake means is provided in the form of a sleeve 23 at the outer end of the housing, and has an intake pipe or conduit 24 mounted thereon, a suitable air controlling means 25, as a damper or the like, being interposed in either said conduit or said sleeve. The conduit 24 is preferably arranged to bring in cold air, from the outside of the building; or may be arranged to take in partly cold air from the outside and partly returning warm air from the rooms of the building; or the conduit may be omitted and the air

taken in direct through the sleeve from the furnace room; or the air may be taken in from any combination of suitable places.

Means for driving or forcing the air to circulate in the system is provided in the form of an electric fan 26 driven by its motor 27 which is connected with a suitable source of power by the electric conductor 28 extending through a suitable opening in the housing. The fan is bolted or otherwise suitably fastened to the housing, and placed across the front opening of the directing member 18, so as to force the outer air through said member and also to draw partly warmed air through passages 22. A door 30 is provided in the housing for conveniently mounting the electric fan and to afford ready access thereto, such door may be mounted slidably in flanges 31 or in any other suitable manner.

From the above disclosure it becomes apparent that the circulation of air from the furnace to the rooms of the building, and through the entire system, is suitably increased, and that such increase may be regulated by regulating the speed of the fan, through the motor, and that even when the furnace fire is so low that normally the circulation would stop, my apparatus will force the circulation to continue. It is fully apparent that my apparatus will stimulate and speed up the circulation in the entire system and will increase the inflow of cold air through the usual cold air intake ducts commonly provided on the furnace. And by bringing more fresh air into the system will also aid in ventilating the building. It is also apparent that the device will supply an additional amount of fresh air through the conduit 24 into the heating system, by gravity of the colder air, even though the fan is not in operation.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In combination with a hot air furnace having an outer casing with an opening provided therein, a device mounted in said opening and comprising means for taking in cool air, means for directing said air upwards within said casing, means on the inward wall of said air directing means for also leading air against the inner wall of said casing, means for conducting warm air directly from the furnace casing into said device, and

means for forcing the circulation of air through said device.

2. In combination with a hot air furnace having a fire pot and an outer casing with an opening cut therein, a device mounted in said opening and comprising means for taking in cold air, means for controlling the amount of said cold air taken in, means for taking in warm air from the furnace casing into said device, and a curved wall with a slot and lip thereon for directing said air diagonally upwards against the fire pot in said casing.

3. In combination with a hot air furnace having a fire pot and an outer casing surrounding the same and provided with an opening, an air circulating device comprising means for mounting it in said opening, said mounting overlapping flanges including means adapted to fit said device on various sized openings and furnaces, and means for taking in external cool air.

4. In combination with a hot air furnace having an outer casing with an opening cut therein, an air circulating device comprising a housing provided with means for taking in air and directing it diagonally upwards in said casing, means for mounting said housing in various sized openings and on various sized furnaces, said mounting means including a curved flange for fastening the housing to the casing wall and clamping members with a plurality of over-lapping flanges for clamping the casing wall there-between.

5. In combination with a hot air furnace having an outer casing, an air circulating device comprising means for mounting it in said casing, means for taking in external cool air, means for taking in warm air from within said casing, means on said device for forcing circulation of air, and means on said device permitting convenient access to said forcing means.

6. An air circulating device for a hot air furnace said device comprising a housing mountable in the furnace casing, a fresh air intake on said housing external of said casing, an air outlet connected with said intake for directing air upwards within said casing, air intake means surrounding said outlet for conducting warmed air from the casing into said device, and means to force said air to circulate.

7. An air circulating device for a hot air furnace, said device comprising a housing mountable in the furnace casing and provided with means for mounting it on various sized casings, an air intake on said housing, an air outlet leading from said intake and directed upwardly, means for forcing the air to circulate, and a door on the side of said housing for introducing said air forcing means and for admitting convenient access thereto.

8. An air circulating device for a hot air

furnace, said device comprising a housing, an air intake on said housing air outlet means leading from said intake and having a curved wall for directing air diagonally upwards, a slot and lip on said wall for also directing air diagonally upwards, an air intake at each side of said outlet means, means for forcing the circulation of said air, and operable means on said housing for admitting convenient access to said air forcing means.

9. An air circulating device for a furnace provided with an air circulating system, said device comprising an outer member con-

nected with said circulating system, an inner member mounted in said outer member and provided with a plurality of openings arranged to direct air upwardly at separate points, and inlets on said device for taking in air from the exterior and also directly from the interior of said circulating system.

In testimony whereof I have signed my name to this specification in the presence of two subscribing witnesses.
